UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

EMERGENCY-BRAKE.

SPECIFICATION forming part of Letters Patent No. 783,508, dated February 28, 1905.

Application filed June 16, 1904. Serial No. 212,779.

To all whom it may concern:

Be it known that I, FRED B. COREY, a citizen of the United States, residing at Schenectady, county of Schenectady, State of New York, have invented certain new and useful Improvements in Emergency-Brakes, of which the following is a specification.

My invention relates to improvements in means for automatically controlling motors by power-actuated brakes in case of an emergency, and is intended for use especially in connection with electrically-propelled vehicles or trains equipped with "automatic" air-brake systems in which an equalizing-reservoir is used.

In my application for Letters Patent, Serial No. 148,902, filed March 21, 1903, I have disclosed controlling means for such a vehicle comprising means operative upon the release of the controller-handle by the motorman for cutting off the power from the motors, for breaking the connection between the motorman's valve and the train-pipe, and for exhausting the train-pipe, so as to apply the brakes. An emergency stop is thus produced in case of sickness, death, or accident to the motorman. It is not always desirable, however, that a severe emergency application of the brakes should be produced; and the object of my present invention is to provide means for obtaining a more gradual application of the brakes upon the release of the controller-handle by the motorman in those systems in which an equalizing-reservoir is employed. I accomplish this by providing a valve controlled by the motorman in any suitable manner—for example, through the controller-handle—and arranged to connect the equalizing-reservoir to atmosphere whenever the motorman becomes incapacitated. By this means a more gradual application of the brakes is produced than is the case where the train-pipe is directly connected to atmosphere.

My invention will best be understood from the accompanying drawings, in which—

Figure 1 shows diagrammatically an automatic air-brake system provided with an emergency-valve in accordance with my invention. Fig. 2 shows a cross-sectional ele-

vation of the valve, and Fig. 3 shows a cross-sectional plan view of the same.

Referring first to Fig. 1, V represents the usual engineer's valve, connected to the equalizing-reservoir E, to the train-line L, and to the main reservoir R. The engineer's valve is a standard Westinghouse valve of the type described in patent to Westinghouse and Moore, No. 401,916.

C represents the compressor for charging the main reservoir.

T represents a triple valve connected to the train-line L, and B and A represent the brake-cylinder and auxiliary reservoir, respectively, connected to the triple valve.

D represents the emergency-valve, mounted on the controller-easing F and connected to the equalizing-reservoir by a pipe e. Valve D is also provided with an exhaust-pipe a, leading to atmosphere.

The construction of valve D is clearly shown in Figs. 2 and 3. The construction of this valve, which forms no part of the present invention, is clearly described in Patent No. 755,750, issued to me March 29, 1904. I shall, however, give a short description of this valve here. The pipe e from the equalizing-reservoir opens into a chamber 1, which is separated from the chamber 5 by the valve 2, which is normally held on its seat, as shown, by the spring 4. The air-pressure in chamber 3 above valve 2, which is connected to chamber 1 by a small passage, as shown, assists in holding the valve 2 on its seat. The chamber 5 is connected to atmosphere by pipe a. The chamber 3 is connected by a passage 6 (shown in Fig. 3) to a chamber 7, which is normally closed by a valve 8, which is pressed upon its seat, as shown, by the spring 9. The valve 8 carries a spindle 10, which is channeled for a portion of its length, as shown, so that when valve 8 is raised chamber 7 is connected to passage 11, which leads to atmosphere. Spindle 10 projects beyond the casing of valve D. The controller-operating mechanism is so arranged that when the handle is released spindle 10 is engaged and pushed inward, connecting chamber 7 to atmosphere. The connection between the controller-handle and

spindle 10 is not shown, since it is clearly described in Patent No. 755,750, above referred to, and since the specific form of connection employed forms no part of the present invention. When chamber 7 is connected to atmosphere, chamber 3 is exhausted, and since the passage between chambers 3 and 1 is too small to equalize the pressure quickly, the greater pressure on the under side of valve 2 raises it 10 from its seat, connecting pipe *e* through chambers 1 and 5 to atmosphere. The pressure in the equalizing-reservoir is thereby reduced and a gradual application of the brakes is obtained.

15 As has been said heretofore, the construction of valve D forms no part of the present invention, and other forms of emergency-valve may be used without departing from the spirit of my invention. I aim in the appended claims 20 to cover all such modifications which are within the scope of my invention.

What I claim as new, and desire to secure by Letters Patent of the United States, is—

25 1. In an "automatic" air-brake system employing an equalizing-reservoir, means independent of the engineer's valve for exhausting the equalizing-reservoir.

30 2. In an "automatic" air-brake system for electrically-propelled vehicles, employing an equalizing-reservoir, a valve arranged to exhaust the equalizing-reservoir, and means under the control of the motorman for causing said valve to be operated.

35 3. In an "automatic" air-brake system employing an equalizing-reservoir, in combination with a motor-controller, a valve controlled from the motor-controller and adapted and arranged to connect the equalizing-reservoir to atmosphere.

40 4. In an "automatic" air-brake system, in combination with a motor-controller, an equalizing-reservoir, an exhaust-port therefor, and

45 a valve controlled from the controller-handle and adapted and arranged to open said exhaust-port to atmosphere.

50 5. In an "automatic" air-brake system, in combination with a motor-controller, an equalizing-reservoir, and a valve operative upon the release of the controller-handle by the motorman and adapted and arranged to connect said equalizing-reservoir to atmosphere.

55 6. In an "automatic" air-brake system, in combination with a motor-controller, an equalizing-reservoir, a connection from the equalizing-reservoir to atmosphere, a valve in said connection, and means actuated upon the release of the controller-handle by the motorman for opening said valve.

60 7. In an "automatic" air-brake system, in combination with a motor-controller, an equalizing-reservoir, a valve independent of the engineer's valve adapted and arranged to exhaust the equalizing-reservoir, and means actuated upon the release of the controller-handle by the motorman for opening said valve.

65 8. In an "automatic" air-brake system, an equalizing-reservoir, a normally open connection from the equalizing-reservoir to atmosphere, and means independent of the engineer's valve for controlling such connection.

70 9. In an "automatic" air-brake system for vehicles, an equalizing-reservoir, a valve adapted and arranged to connect said reservoir to atmosphere, a lever normally under the motorman's control in the operation of the vehicle, and operative connections between the said valve and said lever.

In witness whereof I have hereunto set my hand this 14th day of June, 1904.

FRED B. COREY.
